FOOD WARMER

Marsh P. Duke, University City, Mo., assignor to
Duke Manufacturing Company, St. Louis, Mo.,
a corporation of Missouri

Application February 3, 1939, Serial No. 254,393

2 Claims. (Cl. 126—211)

This invention relates to food warmers, and with regard to certain more specific features, to food warmer or steam table tops.

Among the several objects of the invention may be noted the provision of a food warmer which has a basic form, in connection with which a so-called wet or dry form of heating arrangement may be used; the provision of a steam table of the class described in which the top is removable and useful for either the dry or wet form and which removably holds covers or top plates neatly and in a flush position; the provision of apparatus of the class described in which the covers are of simple and rigid form; and the provision of apparatus of the class described which lends itself easily to adaptation to its various intended forms. Other objects will be in part obvious and in part pointed out hereinafter.

The invention accordingly comprises the elements and combinations of elements, features of construction, and arrangements of parts which will be exemplified in the structures hereinafter described, and the scope of the application of which will be indicated in the following claims.

25 In the accompanying drawings, in which are illustrated several of various possible embodiments of the invention,

Fig. 1 is a plan view of the warmer, on a reduced scale.

30 Fig. 2 is a vertical longitudinal section on an enlarged scale, taken on line 2—2 of Fig. 1;

Fig. 3 is a vertical cross section taken on line 3—3 of Fig. 1 and on the same scale as Fig. 2;

35 Fig. 4 is a fragmentary horizontal section taken on line 4—4 of Fig. 2 with insulation removed;

Fig. 5 is a view similar to Fig. 2 on an enlarged scale, illustrating an alternative form of the invention; and,

40 Fig. 6 is a vertical cross section taken on line 6—6 of Fig. 5.

Similar reference characters indicate corresponding parts throughout the several views of the drawings.

45 Since many of the details of the drawings refer to closely adjacent sheets of metal, such portions have been exaggerated in their relative spacings, in order to clarify the description. Furthermore, certain beaded, rolled, and other joints are exaggerated, and it is to be understood that actually they are in many instances more compact than shown.

50 Referring more particularly to Figs. 1—4, there is shown at 1 a top frame. The peripheral portions 3 of this frame are formed as inverted U-shapes providing a guide to effect placement of the frame upon the upper edge of the table which is box-like and hollow in form, as will appear.

55 It is to be understood that equivalent

downwardly concave shapes may be substituted for the U-shape.

Inside of the inverted U-shape 3, the frame 1 is provided with an inwardly directed, horizontal flange 7 to which are attached cross channels 9. The cross members 9 are also U-shaped but in this case the open portions of the U-shapes are upwardly directed, the closed portions resting upon said flange 7. Thus the channels are concave upward. The ends of the members 9 are spaced from the peripheral U-shaped edge 3, as shown at 11 (see particularly Fig. 3).

The crossbars 9 and the peripheral frame 1 are so related as to provide a plurality of quadrilateral openings for covers, two of which are shown for example and indicated at 13 and 15 in Fig. 1. The third opening at the right in Fig. 1 is shown without a cover. These covers in general consist of a horizontal sheet 17 in which a suitable opening is cut to receive and support a suitably formed dish. For example, the plate 13 is shown with two round openings 19 for round dishes and the plate 15 is shown with a rectangular opening 21 for a rectangular dish.

It will be understood that the plates, or some of them, may be flat and without any adapter opening, to function merely as a support for dishes and the like. The various top plates are the same size and interchangeable.

Each plate, such as 13 and 15, is provided about its periphery with a downwardly directed flange 23. These flanges at their longitudinal portions rest either in the U-shaped members 9 where they abut by pairs, or upon the flange 7 of the frame 1, as the case may be (see Fig. 2, 35 for example). The end portions of the flanges 23 are positioned between the ends 11 of the U-shaped cross members 9 and the side of frame 1 (see Fig. 3).

The described top construction permits easy removal of the top plates for cleaning. When replaced, they assume flush positions with respect to the tops of the U-shaped portions 3 and with respect to each other. It will be understood that the length of the table may be made to accommodate fewer or more of the rectangular tops such as 13, 15.

The sides of the table are shown at 25 (Figs. 3 and 4). These are turned in at their lower edges as shown at 27 to support a bottom 29 which is removable for reconstruction purposes.

At the corners the bottom 29 supports insert plates 30 for supporting insulation 45, to be referred to hereinafter. An angle brace is shown at 32.

Turned-in ends 26 of the sides 25 are attached to the inturned parts 57 of end panels 33.

The parts 57 form what may be referred to as legs which are integral with the end panels 33. Or, the legs may be said to be integral portions of U-shaped end panel 33 (Fig. 4). Both the

55

60

sides 25 and the end panels 33 have at their upper edges inwardly turned flanges 31 upon which an edge of flange 5 rests.

The flange 5 is attached to a water compartment or inner box 35 which has an outlet drain plug 37. Its bottom 39 rests upon upper, turned-in flanges 41 of a flue piece 43. The flue is open at its top as indicated, being closed in by the bottom 39 of the box 35 to form a passage.

10 Between the flue piece 43 and the lowermost bottom 29 is inserted heat insulating material 45 such as asbestos, rock wool or the like. Similar material is inserted between the sides of the water box or pan 35 and the sides 25 and end panels 33 respectively. However, at the end of the flue piece 43 (see the left end of Fig. 2) no insulating material is inserted, and a passage 47 is thus left to communicate with the flue piece 43. Openings 49 permit products of combustion to escape at this point. The other end of the flue piece 43 communicates with an inlet opening 51 in which are located gas burners 53. These burners 53 are located on an inlet manifold 55 which is supported between the turned-in leg portions of the U-shaped panels 33.

From the above it will be seen that when the burners 53 are lighted air is drawn in around them through the passage 51. The products of combustion flow through the flue piece 43 as indicated by the arrows in Fig. 2. This keeps hot water which is carried in the pan 35 in order to heat the vessels of food or the like which are inserted into the openings such as 19 and 21.

Within the legs 51 are brackets 59 for feet 35 61. These also support a shelf 63 between the legs 51, the shelf being also connected to the end panels 33.

The box 35 is removable, as is also the flue member 43. This also permits removal of the insulation 45 and gas manifold 55 with burners 53. Then, after removal of the bottom 29, the parts to be described in connection with Figs. 5 and 6 may be inserted.

Referring now more particularly to said Figs. 45 5 and 6, like numerals designate like parts. The purpose of this alternative construction is to provide a heating table within which there is no pan carrying any liquid, but in which the heat is applied directly to the food containers in the 50 openings such as 19 and 21. Claims drawn to this part of the construction will be found in my United States patent application, Serial No. 308,937, filed December 13, 1939, for food warmer. In this case, a box-like inner structure 65 is 55 employed, also having a flange 5 about its top for resting upon the upper edge of the outer box or table, as in the case of Figs. 1-4. This inner box has a bottom 67. Below the bottom 67 is a table bottom 69 supported by cross members 71. The supports 71 rest upon the turned portions 27 mentioned in connection with Figs. 1-4. Insulating material 73 is employed between the two bottoms 67 and 69 and between the sides 65 and 25 and end-wise between the sides 65 and the 65 ends 33.

Passing through the spaced bottoms 67, 69, and through the insulation therebetween, are open thimbles 74 held up by beads 72. At the lower ends of the thimbles 74 are located gas burners 75, the latter being fed from a gas manifold 77. The manifold 77 is supported upon the members 71 and by a cleat 79.

Above the bottom 67, horizontal radiator plates 81 are arranged upon supports 83 in order to ab-

sorb the heat and radiate it throughout the compartment made by the box 65.

In order to convert the device from the so-called wet form, of Figs. 1-4, to the so-called dry form, of Figs. 5 and 6, it is only necessary to remove the top or cover 1, the water pan 35, flue member 43, insulation 45 and bottom 29. The manifold 55 and burners 53 are also removed.

The cross members 71 of Figs. 5 and 6 are then applied, together with the manifold 77 and burners 75. A new bottom 69 is inserted and also the new form of insulation 73. The box 65, 77 is then dropped into position. Finally, the thimbles 74 are inserted, as well as the deflectors 81. The same top 1 is used, including the same covers 15 13, 15, etc.

It will be seen from the above that the same outer box and legs and top are used in both forms of the invention. Thus, only one class of equipment needs to be stocked for the top, in order to sell both types of tables. Of course, different top sizes need to be carried for different sizes of tables. The holes 49 of Fig. 1 are readily made when required in the form of the invention shown in Figs. 1-4.

25

A simplifying feature of the form of the invention shown in Figs. 1-4 is the depressed sump portion 4 adjacent the outlet plug 37 of the water pan 35. This sump not only serves to direct drainage to the outlet plug 37, but also serves to form the inlet 51 of the flue and to increase the heat transfer surface. This is by reason of the fact that the flue member 43 ends short of the sump 4.

In view of the above, it will be seen that the several objects of the invention are achieved and 35 other advantageous results attained.

As many changes could be made in the above constructions without departing from the scope of the invention, it is intended that all matter contained in the above description or shown in 40 the accompanying drawings shall be interpreted as illustrative and not in a limiting sense.

I claim:

1. A food warmer top comprising a frame having a cross section providing a downwardly concave portion, said portion having a substantially flat flange directed inwardly with respect to the frame and providing an upwardly open recess, at least one member forming a cross piece for the frame and being concave upwardly, and a removable top section having a downwardly directed peripheral flange resting in the concavity of said cross piece and upon said inwardly directed flange of the frame, the length of the cross piece being such as to provide space between its ends and the frame to accommodate a portion of the downwardly directed flange of the top section.

2. A top for food warmers and the like comprising a frame having a peripheral portion with a cross section providing a flange directed inwardly with respect to the frame, at least one member forming a cross-piece resting upon the flange and having an upwardly open concavity, at least two removable interchangeable top sections, each having a downwardly directed peripheral flange resting in part upon said inwardly directed flange of the frame, and parts of said flanges of the top sections abutting in said concavity of said cross-piece, the cross-piece being of a length to provide space between its ends and the frame to accommodate portions of the flanges of the top sections.

MARSH P. DUKE.
